STEAM TURBINE

Ernst Gente, Berlin-Siemensstadt, Germany;
vested in the Alien Property CustodianApplication January 3, 1941, Serial No. 373,058
In Germany December 16, 1939

4 Claims. (Cl. 253—79)

This invention relates to the fixing of blade rings for centrifugal machines with radial admission of the working fluid, particularly for steam turbines.

The two main constructional parts of a steam turbine with radial admission of the working medium, i. e., blade ring and disc represent bodies having different masses and surfaces so that these parts when heated, cooled or deformed by external mechanical forces, for instance, by the centrifugal force react in a different manner. For instance, the ring with its small mass and large surface when heated expands quicker than the disc. If a rigid connection would be used between the ring and the disc, such high stresses would result owing to the difference in expansion that the material cannot absorb the same without damaging its texture, so that a rigid connection between the ring and disc must be avoided and such constructions must be used as to permit a free and independent expansion of the ring and disc.

According to United States Patent No. 1,000,097 this connection is obtained by inserting between the blade ring and the disc, thin-walled cylinders the thickness of which is so chosen that, on the one hand, a transfer of heat between the blade rings and the disc is prevented to a considerable extent and that, on the other hand, the blade ring when being deformed is as far as possible free to expand. However, considerable bending stresses occur in the cylinder-shaped connecting piece with increasing enlargement that the material cannot take up the stresses. To meet this requirement the cylinder-shaped ring must be slotted, so that its cross-section is weakened, whereby the tangential stresses are, so to say, split up. Besides other drawbacks the slotting of the ring may impair the steam-tight condition of the structure.

The other possibility of providing a joint between the blade ring and the disc as free as possible is the kidney-shaped intermediate ring employed in the device of United States Patent No. 1,146,183 and which has given satisfactory results in a large number of turbines. This intermediate ring is, however, capable of being improved, insofar as it presupposes a bead joint. Such joints not only cause a stressing of the material beyond its yield point but also easily bring about a non-circular cross-section of the ring. In this case either the faults caused by the out of balance must be put up with or a rather complicated balancing method must be employed in order to ensure a smooth running of the turbine.

From the manufacturing and operating point of view, the joint according to United States Patent No. 1,000,097 would therefore be preferable, provided that it would be possible to eliminate the faults inherent in the joint. The problems resulting therefrom are solved according to the present invention.

If the conditions presented when fixing the blade ring according to United States Patent No. 1,000,097 are investigated, it will be found that the moments which occur in the connecting ring between the blade ring and disc as a result of the enlargement of the blade ring are very great at the point where the blade ring is fixed but then decrease relatively rapidly in the form of a hyperbola. The material is therefore highly stressed at the point where the blade ring is fixed, whereas the other part of the cross-section is only subjected to relatively small stresses. As already mentioned above the high stresses have been reduced by slotting the ring. The above-said drawbacks may be removed according to the invention by a structure wherein the entire cross-section is as far as possible uniformly stressed. If the entire blade ring were so dimensioned as to take up the maximum stress, without any slotting, the above-mentioned drawback would not be removed, since the ring would have to be so amply dimensioned that a rigid connection with the disc would result which would not meet the desired requirements. The resiliency of the ring which provides for the free expansion with respect to the disc must therefore be retained. This may be accomplished according to the invention by the provision of an intermediate ring connecting the blade ring with the disc, the cross-section or thickness of which decreases towards the point where the intermediate ring is secured to the disc, the cross-section being preferably of the triangular form. As already mentioned above the moment curve is similar to that of a hyperbola. Accordingly the contour line of the cross-section is also adapted to the moment curve. It is then possible without slotting the intermediate ring to absorb all stresses without overstressing the material and to utilize at the same time the material of the intermediate ring in a most favorable manner, since its entire cross-section or a substantial portion thereof is uniformly stressed.

In the case of a revolving disc the centrifugal force acting thereon has its point of application in the center of gravity of the blade ring. The centrifugal force tends to shift outwardly the center of gravity of the blade ring cross-section, i. e., the intermediate ring integral with the blade

ring tends to enlarge to a certain extent in the form of a funnel. The centrifugal force resulting from the blades and which therefore causes the intermediate ring to enlarge to a further extent acts in the same direction as the centrifugal force of the blade rings. Consequently, the blade ring has the tendency to assume an inclined position. Difficulties may arise from this condition in maintaining the clearances between the blades, for it is assumed that the sealing clearance has a cylindrical but not a conical form. By applying additional weights to the blade ring or to the intermediate ring or to both, moments may be produced which more or less balance the moments resulting from the two centrifugal forces mentioned above. When selecting these balance weights, the fact must be still considered that the shearing force produced by the enlargement of the intermediate ring produces a moment which opposes the enlargement. It may be necessary under certain conditions to consider this moment when determining the balance weights.

As already mentioned above this form of the invention is based on the proposals to provide balance weights or inertia masses which have been made for different purposes for example, in the U. S. Patent 1,906,697. When fixing the blades according to United States Patent No. 1,146,183 with the aid of kidney-shaped intermediate rings as previously mentioned, the blade centrifugal force the point of application of which is in the center of gravity of the blade causes a twisting of the cross-section of the blade ring about its center of gravity, i. e., the blade with its support assumes then the form of an arc. To straighten the cross-section of the blade ring it has been proposed in this patent to employ additional masses the centrifugal forces of which produce moments in the ring which balance the moments produced by the centrifugal forces of the blades and acting in the opposite direction. However, this refers as mentioned above only to such blades which are secured between two ring groups hingedly connected to the turbine discs, whereas the present invention is based on the fact that the blade ring ends in a thin tubular portion which is secured to the disc.

An embodiment of the invention is shown in the accompanying drawing in diagrammatic form in which Fig. 1 is a longitudinal vertical section through the blade ring, the intermediate ring and the disc, and Fig. 2 is a transverse vertical section on the line 2-2 of Fig. 1.

The blades 1 of a steam turbine with radial admission of the working fluid are firmly held in position by the support or blade ring 2 which ends in an intermediate ring or tubular portion 3. The latter is firmly secured to the carrier member or disc 4 by means of a caulking joint 5 and is prevented from being displaced by a weld joint 6. The centrifugal force P_1 is applied to the center of gravity of the support ring 2 and causes an enlargement of the ring 3. The rim force P_2 produces by the blades acts in the same direction. As a result of the rigid connection between the support ring 2 and the tubular portion 3 thereof, shearing forces P_4 are produced in the latter which tend to oppose the centrifugal forces P_1 and P_2 . In view of the very high stresses to which the intermediate ring 3 is subjected the cross-section of the tubular portion thereof is not made cylindrical as has hitherto been proposed but de-

creases as shown in the drawing from the blade ring 2 to the disc 4. In order to prevent the blades 1 from assuming an inclined position, balance weights are provided which produce the balance forces P_3 and P_5 . In this case the force P_3 balances the forces P_1 and P_2 , whereas the force P_5 balances the force P_4 . The representation of the balance weights is purely diagrammatic. It is not necessary that two balance weights be provided. The two weights may also be combined in a single mass. It is likewise not necessary to arrange the balance mass as shown in the drawing.

The above considerations on the revolving disc 15 of a steam turbine with radial admission of the working fluid apply also to other centrifugal machines with radial admission of the working fluid in which similar conditions occur. The same considerations apply also to the stationary disc in 20 which no stresses due to centrifugal forces but other stresses caused by the unilateral super-atmospheric pressure may occur.

What is claimed is:

1. In a radial flow turbine, the combination 25 of a radially extending rotor disc; a cylindrical blade ring; a plurality of turbine blades carried by said ring; and an elastic ring formed integral with said blade ring and secured to said disc, said elastic ring having a face tapered from the blade 30 ring to the disc, on a curve corresponding to the curve of the moments set up in said elastic ring by the operation of the turbine.

2. In a radial flow turbine, the combination of 35 a radially extending rotor disc; a plurality of turbine blades; and a tubular member axially extending from said disc, and comprising a cylindrical portion at its outer end, serving as a blade ring and upon which said blades are mounted, a reduced cylindrical portion at its inner end, received in and secured to said disk, and an elastic portion disposed between said cylindrical portions and having its outer end of the same thickness as the outer end portion, and so tapered to the reduced thickness of the inner end portion 45 that its cross-sectional area on any radial plane is directly proportional to the stress exerted along said plane by the operation of the turbine.

3. In a radial flow turbine, the combination 50 of a radially extending rotor disc; a cylindrical blade ring; a plurality of turbine blades carried by said ring; and an elastic ring secured to said disc, rigidly connected to said blade ring, and having a cross-sectional area in direct proportion to the shearing force produced in the elastic ring, and the opposing centrifugal force applied to the 55 blade ring and blades, as a result of the operation of the turbine.

4. In a radial flow turbine, the combination of 60 a radially extending rotor disc; a cylindrical blade ring; a plurality of turbine blades carried by said ring; an elastic ring secured to said disc and rigidly connected to said blade ring, the parts being so related that the centrifugal force, caused by the operation of the turbine, is applied to the 65 blade ring and the blades, and resulting shearing force is produced in the elastic ring; and two balancing masses located on said elastic ring adjacent said blade ring so as to counteract the effects of centrifugal force on the blade ring and the blades and shearing force on the elastic ring respectively.

ERNST GENTE.
